UNITED STATES PATENT OFFICE.

OLIVER M. MOWAT, OF MCKEESPORT, PENNSYLVANIA.

DRILL-CHUCK.

No. 824,735.

Specification of Letters Patent.

Patented July 3, 1906.

Application filed May 11, 1905. Serial No. 259,896.

To all whom it may concern:

Be it known that I, OLIVER M. MOWAT, a citizen of the United States of America, residing at McKeesport, in the county of Allegheny and State of Pennsylvania, have invented certain new and useful Improvements in Drill-Chucks, of which the following is a specification, reference being had therein to the accompanying drawings.

10 This invention relates to certain new and useful improvements in drill-chucks; and the invention has for its object to provide a chuck-body wherein novel jaws are employed for gripping and retaining the shank 15 of a drill within the chuck-body.

Another object of this invention is to provide a chuck-body in which a substantially rectangular shank portion of a bit or drill can be easily and quickly secured, novel means 20 also being provided in connection with a chuck-body for accurately holding drills or bits having tapering or cylindrical shank portions, also drills or bits having flattened surfaces or angularly-disposed faces.

25 Briefly described, my improved drill-chuck consists of a body having a plurality of jaws mounted therein adapted to be adjusted by an operating-ring carried by the chuck-body. Some of the jaws of the chuck-body are provided with lugs adapted to engage flat surfaces formed upon the shank of a 30 drill or bit, and in order that the jaws may be adjusted I have cut away a portion of the chuck-body to permit of the movement of the jaws carrying the lugs.

35 The above construction will be hereinafter more fully described and then specifically pointed out in the claims, and, referring to the drawings accompanying this application, 40 like numerals of reference designate corresponding parts throughout the several views, in which—

45 Figure 1 is a perspective view of my improved chuck-body, partly broken away to illustrate the interior formation of the same.

50 Fig. 2 is a transverse sectional view of the chuck-body, illustrating the shank of a drill clamped therein, the operating-ring being removed from the chuck-body. Fig. 3 is a side elevation of the shank portion of a drill, illustrating my improved jaws clamping said drill. Fig. 4 is a side elevation view of the chuck-body; partly in section; and Fig. 5 is a

detail perspective view of a portion of my improved jaws.

55 To put my invention into practice, I employ the ordinary and well-known form of chuck-body 1, which is preferably made of machinery-steel and is provided with tapering ends 2 and 3. The tapering end 3 of the 60 chuck-body is provided with a tapering opening or recess 4, adapted to receive the spindle of a drilling-machine, whereby it can be revolved. The chuck-body is provided with a plurality of jaw-openings 5 5, which are angularly disposed to the longitudinal axis of the chuck-body. The ends of the jaw-openings terminating in the tapering end 2 form a substantially three-winged opening, the walls of said opening intersecting and providing a 65 common opening in the tapering end 2 of the chuck-body. The opposite ends of the jaw-openings terminate in the periphery of the chuck-body adjacent to the tapering end 3 thereof, as clearly illustrated in Fig. 1 of the 70 drawings. In the jaw-openings of the chuck-body are mounted jaws 6, which are made of tool-steel carefully hardened and tempered. Each jaw consists of a cylindrical body portion, the one end of which is cut away to form 75 angularly-disposed surfaces 7 and 7', and the opposite end of the jaws are cut away, as indicated at 8, to form threads 9, that are formed transversely of the jaw and upon an arc corresponding to the circumference of the 80 chuck-body. The jaws are adapted to be mounted in the openings 5 of the chuck-body and the threaded portion of each jaw is adapted to engage a threaded ring 10, mounted in an annular groove 11, formed in the 85 chuck-body, said groove intersecting the jaw-openings and permitting the threaded ring to engage the threads 9 of each of the jaws. A knurled ring 12 is placed upon the chuck-body in engagement with the threaded ring, 90 whereby said ring can be readily revolved to move the jaws within their respective openings.

95 The above construction, as described, is common to chuck-bodies at present used, and my invention resides in the construction of the jaws and the chuck-body now to be described in connection with the chuck-body heretofore mentioned.

100 Heretofore in chuck-bodies wherein three gripping-jaws were employed and manually

operated it has been impossible to grip the shank portions of drills having rectangular or flattened shanks without removing the jaws employed for gripping a cylindrical shank portion and employing specially-constructed jaws for rectangular shanks. In view of the above facts I have devised jaws for chuck-bodies which are capable of gripping cylindrical shanks, as well as shanks of a rectangular form or provided with flat surfaces. In Figs. 2, 3, and 5 of the drawings I have illustrated my improved jaws, and the invention resides in providing one of the angularly-disposed surfaces 7 of two of the jaws with lugs 14 14. These lugs are preferably formed at the rear ends of the angularly-disposed surfaces 7, and the faces 15 15 of said lugs are adapted to lie in a plane horizontal with the adjacent angularly-disposed surface 7' of said jaws.

In the ordinary form of chuck-body the jaw-openings lie at angles substantially one hundred and twenty degrees from one another, and in order that my improved jaws may be advantageously used for the purposes heretofore mentioned it is necessary that two of the openings in which my improved jaws are to be mounted should be constructed closer together or at a greater angle from the third opening of the chuck-body. This construction is necessary that the angularly-disposed surfaces 15 of the jaws can be positioned in planes parallel to one another, whereby the shank of a drill can be properly gripped. In Fig. 2 of the drawings I have illustrated the shank of a drill 16, which is cylindrical and is provided with diametrically-opposed flat surfaces 17 17. These flat surfaces correspond to the sides of an inscribed square of a circle having a diameter equivalent to the cylindrical shank of the drill. In order that the angularly-disposed surfaces 15 15 of the lugs 17 may embrace the flat surfaces of the drill, I have found it necessary to position the jaw-openings 5 5, carrying my improved jaws, closer together in order that the lugs carried by the jaws positioned within said openings will lie in parallel planes.

To accommodate jaws constructed in accordance with my invention within the chuck-body 1, I have found it necessary to cut away the chuck-body upon each side of the openings carrying the specially-constructed jaws. The cut-away portion of one of said openings is illustrated in Fig. 1 of the drawings, and by comparing this figure with Fig. 2 of the drawings it will be observed that the portion cut out of the chuck-body is substantially triangular in form, as designated by the reference-numeral 18. It is only necessary to cut away the chuck-body a short distance upon each side of the jaw-openings, as it is seldom necessary to adjust the jaws a

great distance in order to clamp the flat surfaces of a drill-shank. In placing the jaws within the chuck-body they are preferably placed in the openings 5 5 at the tapered end 2 of the chuck-body, one jaw being placed in at a time.

It is obvious that I have only constructed two of the jaws of the chuck-body in accordance with my invention, it being only necessary to hold the shank of the drill upon two sides when a third jaw is engaging the periphery of the drill-shank, as indicated at 19. The jaws can also be used for gripping tapered shanks, in which instance the sharp edges 20, formed by the angularly-disposed faces 7 and 7' of the jaws, are adapted to engage the periphery of the drill-shanks.

From the foregoing it will be observed that when the shank of a drill or bit is placed within the chuck-body and the operating-ring rotated to move the jaws 6 into engagement with the shank of a bit or drill said shank will be centered within the chuck-body, and after the jaws have once gripped the shank it will be impossible for any longitudinal movement of the drill-shank within the chuck-body to take place. In connection with my improved jaws and chuck-body I may employ a fourth jaw, which may be positioned to engage the peripheral surface of a shank while two jaws constructed with lugs 14 14 may be engaging the flattened surfaces of the shank.

From the above description it is thought that the construction, operation, and advantages of a chuck-body constructed in accordance with my invention will be apparent without further description, and it will be understood that various changes in the form, proportion, and minor details of construction may be resorted to without departing from the spirit of the invention or sacrificing any of the advantages thereof.

What I claim, and desire to secure by Letters Patent, is—

1. The combination with a chuck-body having converging openings formed therein and an operating-ring, of jaws mounted in said openings and adjustable by said ring, the ends of said jaws being provided with angularly-disposed faces, one of said faces on one jaw confronting a face on another jaw lying in a plane parallel therewith, lugs carried by the said two jaws at the rear portion of said faces, said lugs having two of their faces in parallel planes.

2. The combination with a chuck-body having three converging openings formed therein, two of said openings being closer together than each of the same is to the third opening, of jaws mounted one in each of said openings, the ends of said jaws being formed with angularly-disposed faces, means for adjusting said jaws, and lugs carried by the two

jaws which are in the closer relation, said lugs having two of their faces in parallel planes.

3. The combination with a chuck-body, having a tapering end, said body being formed with openings converging in the direction of the longitudinal axis of the body and toward a common line, jaws mounted in said openings, lugs carried by said jaws and having

confronting parallel faces and means to adjust said jaws.

In testimony whereof I affix my signature in the presence of two witnesses.

OLIVER M. MOWAT.
